UNITED STATES PATENT OFFICE.

HARRY RANDOLPH VAN DEVENTER, OF SUMTER, SOUTH CAROLINA, ASSIGNEE, BY
MESNE ASSIGNMENTS, TO SPLITDORF ELECTRICAL COMPANY, OF NEWARK, NEW
JERSEY, A CORPORATION OF NEW JERSEY.

COMBINED IGNITION AND RADIO SYSTEM.

1,186,246.

Specification of Letters Patent.

Patented June 6, 1916.

Application filed April 20, 1915. Serial No. 22,585.

To all whom it may concern:

Be it known that I, HARRY RANDOLPH VAN DEVENTER, a citizen of the United States, residing at Sumter, in the county of Sumter and State of South Carolina, have invented certain new and useful Improvements in Combined Ignition and Radio Systems, of which the following is a specification, reference being had to the accompanying drawing.

This invention relates to combined ignition and radio systems and more particularly to the use of what is commonly termed a "high tension" generator so arranged as to deliver current for jump spark ignition purposes, which can, at the same time, be used as a source of energy for radio transmission in connection with any suitable form of apparatus.

High tension generators or magnetos for ignition are in common use in connection with internal combustion engines. Wireless telegraph systems are often installed on vehicles driven by such engines, for instance, aeroplanes and airships.

My invention, for the sake of illustration, may be considered as applied to an aeroplane engine. Here it will be evident that among its advantages are the elimination of batteries heretofore necessary for supplying the radio equipment, a reduction in weight, as only a single generator for both the engine ignition and the wireless is used; simplicity of connections and apparatus, and a more rugged and reliable source of energy than has heretofore been employed.

There are other objects which will herein-after more fully appear.

In the accompanying drawings, Figure 1 is a view showing the arrangement of an ignition magneto adapted for use in connection with my combined system, and Fig. 2, a circuit diagram of the system.

Like figures of reference denote the same parts wherever they are shown.

Any suitable form of high tension magneto may be employed, either of the wire wound armature type in which the revolving armature carries a primary and secondary winding, or the type of generator in which a revolving element is employed which does not carry the windings, the latter being relatively fixed. I prefer the latter type of

magneto and for the sake of illustration show my system as used therewith. I show here only sufficient parts of said magneto to properly illustrate my invention, as the operation and construction of such a magneto is already well-known to those skilled in the art, except in regard to the special construction herein described and claimed.

1 denotes the usual magnet. 2 the shaft of the rotating element which comprises the magnetic members 3 and 4 of permanent and opposite polarity. Carried on the shaft is the gear 5 which engages distributor gear 6 which carries the rotating element 7 of the distributor arranged to contact in the normal way with the segments 8 and 9 which connect to the spark plug cables, one of which is shown at 10. The rotating element 7 of the distributor is connected to a terminal post 11. The generating coil 12 of the magneto is supported in a movable field structure comprising the pole pieces, one of which is shown at 13, the magnetic end plates 14 and 15 and non-magnetic rings 16 and 17. This structure together with the interrupter mechanism comprising the box or casing 18, the cam 19 and the usual interrupter contacts 20 and 21 is angularly adjustable about the axis of the rotor by means of the handle 22 for the purpose of varying the timing of the ignition.

The coil 12 carries two windings, a primary and secondary, one end of the secondary being grounded on the core of the coil and the free end of same connecting to the contact member 23 which is freely movable with the coil and which engages a fixed contact member 24 carried on the insulated block 25 positioned in the bend of the magnet. The circuit being completed from 23 to 24 is carried from 24 by any suitable means to the terminal 26 and also to a safety spark gap point 27 which is located at sufficient distance from the edge of the magnet 1 to only operate when the gap in the external circuit is excessive. It will now be observed that there is a circuit for the secondary current from the coil by way of contacts 23 and 24 to spark gap point 27 to the magnets or frame of the machine and to the core of the coil, or by way of contacts 23 and 24 to terminal 26 and that if the

latter is connected to terminal 11, the circuit will be completed by way of the traveling contact 7 of the distributor to the various spark plug terminals, two of which are indicated at 8 and 9 and passing over the cables 10, the current will be completed through the spark plugs in the engine and back to the frame of the magnet, a plug being indicated at 28 and the path of the 10 secondary current therethrough being indicated by the connecting dotted lines. It will be observed that terminals 11 and 26 form a gap in series in the secondary circuit of the magneto between the high tension 15 generating winding and the distributor and to these terminals I connect any suitable form of radio transmitting equipment.

I show here diagrammatically the apparatus commonly used in connection with a 20 syntonic system, such as the Braun. Suitable condensers 29 and 30 are employed in connection with the primary 31 of a suitable transformer, the secondary 32 of which connects to the radiating wires 33 and 34 which 25 may be of suitable inductance and capacity in accordance with the results desired. Any suitable method of operating the sending circuit may be employed. I show a key 35 arranged in an operative manner.

30 Motors as now commonly constructed have 6 and 8 cylinders, and in the case of the latter running at ordinary speeds and driving the magneto having a distributor arranged for 8 cylinders, approximately 35 12,000 impulses per minute will flow in the circuit between the coil 12 and the moving member 7 of the distributor. These impulses it will be observed may pass through the radio equipment consisting of the condensers 29 and 30 and the winding 31 and the passage of this current may be suitably deflected from said condensers and winding by the operation of the key 35, or if it is not desired to use the radio equipment, key 35 40 may be arranged to be permanently closed in any well-known manner. And it is obvious that if the key 35 is operated at the usual rate of speed as used in hand telegraphy that the ignition circuit will not be 45 materially interfered with. In fact by the proper adjustment of the condensers 29 and 30 and the coil 31, I find it practical to operate the system as shown with practically no effect on the ignition as the flow of current through the spark plugs is practically uninterrupted.

One serious objection to a combined system as just described has been the attempt to utilize generators in which the intensity 50 of the spark was varied in unison with the ignition timing. In the preferred form of generator here shown the coil 12 is angularly adjustable about the axis of the magneto shaft for timing purposes and the intensity 55 of the current is not varied by the position

of said coil in relation to the rotating element, but remains constant for any given speed, hence the electrical characteristics of the radio equipment connected to the magneto may be suitably adjusted to insure the 70 desired results. This desirable result is particularly easy to attain in connection with aeroplanes in which the engine is driven at a fixed speed.

The diagram, Fig. 2, shows the connections of the entire apparatus, 36 and 37 being the primary and secondary windings of the magneto. 38 is the condenser across the interrupter contacts 20 and 21. 19 is the cam operating the interrupter. It will be 80 seen that one end of the secondary winding 37 connects to the terminal 26 and spark gap point 27 and that the movable member 7 of the distributor is connected to terminal 11. 26 and 11 connect to the wireless equipment as shown.

It will be understood that many modifications and departures can be made from the mechanical arrangement as here shown. Therefore the invention consists broadly in 90 the combination between a high tension ignition magneto and a radio transmitting equipment and more specifically with means whereby the radio equipment may be connected in the high tension circuit of the 95 magneto without rendering the current flowing therein unfit for ignition purposes, and also the arrangement whereby the timing of the magneto may be varied without affecting the intensity of the current in the 100 radio circuit.

Having thus described my invention, I claim:—

1. The combination with a generator having primary and secondary circuits, of a 105 distributor, ignition spacing devices connected thereto, a circuit between said secondary circuit and distributor, spark gap terminals in said circuit mounted on said generator and radio signaling means connected to the terminals of said spark gap.

2. The combination with a generator having primary and secondary windings and circuits, of a distributor, ignition sparking devices connected thereto, a circuit between said secondary circuit and said distributor, a safety spark gap between said circuit and the frame of the generator, a spark gap in series in said secondary circuit between said secondary winding and distributor, and radio signaling means connected to said last mentioned gap.

3. In combination with an ignition dynamo having a high tension winding, one end whereof is connected to the frame of said dynamo, a terminal mounted on said dynamo and connected to the free end of said winding, radio signaling means connected to said last terminal, and a circuit including a spark gap between said last terminal and

the frame of said dynamo for generating electric oscillations in the radio-signaling means.

4. In combination, an ignition dynamo comprising primary field, a normally fixed secondary field structure having adjustable poles, revoluble means associated with the primary field for directing the flux therefrom through said secondary poles alter-
10 nately and oppositely, a coil on said struc-
ture, a lever connected to the secondary field and adapted when moved to turn the same so as to effect an angular displacement of the secondary field poles to advance and
15 retard the spark, and radio signaling means connected to said coil.

5. In combination, an ignition dynamo comprising field magnets, a normally fixed adjustable generating coil in the space with-
20 in the magnets, an insulating block mounted within the field magnets, and adjacent said coil, a fixed contact on said block, a movable contact carried on the coil together with circuit connections completed through said
25 contacts, said connections including radio signaling means.

6. In combination with an ignition dynamo having a permanent magnetic field

structure with a power shaft journaled in bearings in its opposite limbs, a rotor, a 30 generating coil between the limbs separate from said rotor, an interrupter and a distributor outside one limb and connected to the power shaft, a circuit connecting said coil and distributor, radio signaling means 35 connected to said circuit and means in said circuit for generating electric oscillations for the radio-signaling means.

7. In combination, an ignition dynamo, a generating coil, a current supply circuit 40 therein, a plurality of igniting devices connected therewith, radio signaling means connected to said supply circuit, and means whereby the timing of said igniting devices may be varied without affecting the intensity of the current in said supply circuit, said means including a timing lever external 45 said dynamo whereby said generating coil may be axially adjusted in relation to the shaft of said dynamo.

In testimony whereof I hereunto affix my signature in the presence of two witnesses.

HARRY RANDOLPH VAN DEVENTER.
